UNITED STATES PATENT OFFICE.

EMIL HARTMAN, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

SLIDING-TONGUE BUCKLE.

1,004,166.

Specification of Letters Patent. Patented Sept. 26, 1911.

Application filed October 7, 1910. Serial No. 585,842.

To all whom it may concern:

Be it known that I, EMIL HARTMAN, a citizen of the United States, residing at Baltimore, in the State of Maryland, have 5 invented a certain new and useful Improvement in Sliding-Tongue Buckles, of which the following is a full, clear, and exact description.

The object of this invention is to provide 10 a buckle in which instead of a pivoted tooth-like tongue, or a fixed stud, or a lever, for engaging the strap or belt end to fix the parts in adjusted position, there is a substantially flat tongue, applied to the buckle 15 frame, and capable of a rectilinear or sliding movement upon the frame in such way as to clamp the strap or belt end between itself and an adjacent portion of the frame.

The novel features are the sliding tongue, 20 the complementary parts of the buckle frame, and the manner in which the tongue and the frame are assembled and coöperate to effect the adjustment and retention of the strap or belt or other article to which the buckle 25 is applied the tongue and frame being permanently fixed or assembled before being delivered to the trade.

In the accompanying drawings, illustrating 30 the invention, in the several figures of which like parts are similarly designated, Figure 1 is a top plan view, Fig. 2 is a bottom plan view, Fig. 3 is a longitudinal section with the strap ends in place, and Fig. 4 is a perspective view, parts detached, showing 35 one form of the invention. Fig. 5 is a top plan view, Fig. 6 is a bottom plan view, Fig. 7 is a longitudinal section and Fig. 8 is a perspective view, parts detached, illustrating a modification. Fig. 9 is a top plan 40 view, Fig. 10 is a bottom plan view, Fig. 11 is a longitudinal section indicating the manner of assembling the tongue and frame, Fig. 12 is a longitudinal section showing the 45 parts assembled, and Fig. 13 is a perspective view, parts detached, illustrating still another modification of the invention.

The genus illustrated here may be said to consist of a buckle frame having a slidable tongue and a supporting lug extending longitudinally within the frame and so disposed with relation to one end of the frame as to admit of the tongue being drawn toward said end of the frame by strain on the engaged strap or belt, to thereby clamp 55 the strap or belt and hold it in engaged po-

sition, and the drawings illustrate three species of this genus. It is to be understood, however, that the invention is not exhausted by these illustrations, but is capable of assuming many other specific forms 60 coming within the scope of the claims following. Moreover, details of construction, contour and arrangement are variable to suit the demands of the trade. With this statement of the intended scope of the invention, and 65 its generic characteristics I will proceed to describe said invention as illustrated in the drawings.

The frame 1 is substantially the same in the several forms, and comprises side bars 2, 70 end bars 3 and 4, a cross-bar 5, and a cross bar 6 near the end bar 3, and having the substantially central, longitudinally extending tongue-supporting lug 7. As shown in Figs. 1 to 4 and 9 to 13, this lug extends toward the end bar 3, but as shown in Figs. 5 to 8, it may extend toward the opposite end of the frame. The free edge of the lug may be straight as seen at 8, Figs. 2 and 4, or it may be concave as seen at 9, Figs. 9, 10 and 75 13, or of other profile. Its supporting cross-bar may be depressed from the superficial plane of the outer surface of the frame, as in Figs. 1 to 4, or it may lie in said plane, as in the other views. The cross-bar 5 preferably 80 is thus depressed, so as to take the loop of the anchoring strap and the overlying strap end without objectionable protrusion. The lug 7 is an integral part of the cross-bar 6, and is formed by separating it from the 85 side bars by means of the slits 10.

The inner edge of the end bar 3 may be provided with the rearwardly turned lip 11, Figs. 2 to 4, to arrest the outward movement of the sliding tongue, but this lip is 90 necessary mainly when the cross-bar 6 and its lug 7 are depressed.

The sliding tongue 12, comprises side bars 13, and end bar 14, having a rearwardly turned inside lip 15 which affords a finger 100 hold in operating the tongue, and an elevated end bar 16 having the rearwardly turned convergent clips 17 which enter the slits 10 and embrace the lug 7 so as to effect a sliding engagement of the tongue with 105 said lug. The edge 18 of the end bar 16 cooperates with the lip 11 first to arrest the movement of the tongue in that direction, and second, and primarily, to clamp the strap end between the two. 110

As shown in Fig. 3, the buckle may be applied to a strap end 19 by looping said end around the cross-bar 5 and fastening its folds, and the other strap end 20 is passed up through the spaces between the end bars 3 and 14 and the next adjacent bars of the frame and tongue respectively, and then over the bars 16 and 5 and then down through the space between the cross-bar 5 and the end bar 4, and then when strain is applied to the strap ends the sliding tongue will move toward the end bar 3 and clamp the strap end 20 between the adjacent edges of the end bars 3 and 16. The lips 11 and 15 put a bend or bight in the strap end 20 whereby the clamping effect of the tongue is enhanced.

The buckle shown in Figs. 5 to 8 is substantially and in principle like that just described, excepting that the lug 7 projects toward the end bar 4, and the clips 17 meet over instead of under said lug, and their end bar is not elevated; the frame has no lip, and its sides may be provided with rearwardly extended flanges 21 to guide the tongue by contact with its side bars. The edge 22 of the end bar 16 may be concaved to gain more room for the passage of the strap end. The flanges 21 may be only as long as the side bars 13 of the tongue, as shown in Fig. 6.

In the constructions described, it may be necessary to bend the lips over the lugs in order to apply the tongue to the frame, and while this is entirely feasible, it presents some difficulties from a manufacturing point of view that would be obviated with a consequent reduction in manufacturing costs if the tongue and frame could be made and finished separately and then assembled, and this is accomplished in and by the construction shown in Figs. 9 to 13. It is to be understood that these buckles are made of soft steel, usually, and the parts are stamped out, cleaned, annealed or case-hardened, and polished, and the finished articles are more or less springy and yet sufficiently rigid to withstand the strains of use. Taking advantage of this springiness, I make the frame and tongue separately (as is true of all of the forms shown), and finish them and then spring the finished tongue onto the finished frame to effect assembling and produce a finished buckle, ready for use. The frame is substantially like that shown in

Figs. 1 to 4, but without the lip 11, and the tongue differs from that shown in Figs. 1 to 4 mainly in detail. As indicated in Fig. 11, the finished tongue is applied to the finished frame by forcing or springing its clip end 60 onto the lug 7 from the rear, until it takes the operative position shown in Fig. 12, the clips yielding sufficiently to permit such operation. The side slits 23 of the clips facilitate this springing of the tongue onto 65 the lug, in addition to affording stops and guides for the tongue. The clips and the adjacent part of their end bar constitute a spring loop, in effect.

As sufficiently indicated, the invention is 70 susceptible of variations in structural details and in arrangement of parts as defined by the claims following.

What I claim is:—

1. A sliding tongue buckle, having a 75 frame provided with side bars, end bars, a bar to which the strap end is applied, and a tongue-supporting cross-bar having a lug extending lengthwise of the frame and separated from the side bars throughout its 80 length on both sides, and a sliding tongue arranged parallel with the frame on one side of the lug and having an end bar whose edge next to the adjacent end bar of the frame cooperates with the edge of said end bar of the 85 frame to grip the free end of the strap as strain upon such strap end slides the tongue toward the adjacent end of the frame, said tongue unremovably applied to said lug and solely in sliding relation to it and the 90 frame by means of clips on its said end bar forming a loop embracing said lug and holding said tongue in parallelism with the frame while permitting exclusively the 95 aforesaid rectilinear sliding movement. 95

2. A sliding tongue buckle, having a 100 frame provided with a tongue-supporting cross-bar and a lug on said cross-bar, and a tongue having clips forming a spring loop adapted to be sprung onto said lug on the cross-bar to connect the frame and tongue in operative relation.

In testimony whereof I have hereunto set my hand this sixth day of October A. D. 1910.

Correction in Letters Patent No. 1,004,166.

It is hereby certified that in Letters Patent No. 1,004,166, granted September 26, 1911, upon the application of Emil Hartman, of Baltimore, Maryland, for an improvement in "Sliding-Tongue Buckles," an error appears in the printed specification requiring correction as follows: Page 2, line 33, for the word "lips" read *clips*; and that the said Letters Patent should be read with this correction therein that the same may conform to the record of the case in the Patent Office.

Signed and sealed this 17th day of October, A. D., 1911.
